UNITED STATES PATENT OFFICE

132,277

DESIGN FOR A COMBINED TOY FIGURE AND PARACHUTE

Elvy Kalep, New York, N. Y.

Application February 2, 1942, Serial No. 105,567

Term of patent 14 years

To all whom it may concern:

Be it known that I, Elvy Kalep, a citizen of the Republic of Estonia and a resident of the city of New York, county of New York, State of New York, have invented a new, original, and ornamental Design for a Combined Toy Figure and Parachute, of which the following is a specification, reference being had to the accompanying drawing, forming a part thereof.

I claim:

The ornamental design for a combined toy figure and parachute, as shown.

ELVY KALEP.
